United States Patent Office

Des. 231,716
Patented June 4, 1974

231,716

CONFECTION STICK

John F. Severson, Federal Bldg., Bismarck, N.D. 58501

Filed Apr. 18, 1972, Ser. No. 245,290

Term of patent 14 years

Int. Cl. D1—99

U.S. Cl. D1—99

Fig. 1

Fig. 2

Fig. 3

Fig. 4

Fig. 5

FIG. 1 is a perspective view of a confection stick showing my new design;

FIG. 2 is a top plan view thereof;

FIG. 3 is a side elevational view thereof;

FIG. 4 is an end view thereof; and

FIG. 5 is a sectional view taken substantially upon the plane indicated by the section line 5—5 of FIG. 3.

I claim:

The ornamental design for a confection stick, substantially as shown.
